CLAIM

I claim the ornamental design for a handheld metal cooking ring disposable between opposed cooking surfaces, as shown and described.

DESCRIPTION

FIG. 1 is a top side perspective view of a handled metal cooking ring disposable between opposed cooking surfaces showing my new design in accord with my invention; FIG. 2 is a top plan view thereof, the bottom plan view being the mirror image thereof;

FIG. 3 is a front side elevational view thereof;

FIG. 4 is a rear side elevational view thereof;

FIG. 5 is a left side elevational view thereof; and,

FIG. 6 is a right side elevational view thereof.
